UNITED STATES PATENT OFFICE

WILLARD CHARLES FRENCH, OF MILTON, MASSACHUSETTS, ASSIGNOR TO HOOKLESS FASTENER COMPANY, OF MEADVILLE, PENNSYLVANIA, A CORPORATION OF PENNSYLVANIA

TAPE FOR STRINGERS FOR SEPARABLE FASTENERS

Application filed December 14, 1927. Serial No. 239,855.

My present invention relates to improvements in stringers for separable or slide fasteners and I will herein more specifically refer to those phases of my inventions which are more particularly involved in a woven stringer of this type.

In my previous application for Letters Patent, Serial No. 161,626, filed January 17, 1927, I showed and described stringers of braided type. In my present invention I will show types of woven stringers which I believe to be entirely new in this art. In the drawings I have shown characteristic weaves embodying my invention and have endeavored diagrammatically to indicate the proper practices in obtaining such weaves. Throughout these drawings and in the accompanying specification like reference characters are employed to indicate corresponding parts, and 20 in the drawings:

Fig. 1 is a view of a separable fastener system in which are embodied a pair of stringer sections in accordance with my invention.

Fig. 2 is a diagrammatic weave indication of two picks of a cross section of such a stringer, made with a single shuttle.

Fig. 2' is a diagrammatic cross section of the following two picks in such stringer.

Figs. 2^b, 2^c and 2^d are diagrams showing the path of the shuttle threads in the manufacture of the same stringer.

Figs. 3, 3^a, 3^b and 3^d are similar diagrams to those in Figs. 2, 2^a, 2^b, 2^c and 2^d, showing 35 a construction for two shuttles working at once in the same direction.

Figs. 4, 4^a and 4^d are similar diagrams of a construction for three shuttles working at the same time, one in opposite direction 40 to the other two, and

Fig. 5 a plan and Fig. 5^a a cross section of the beaded edge and a section of the tape proper showing diagrammatically a characteristic doup or leno weave by means of 45 which cords may be affixed to opposite sides of one edge of a tape as it is woven.

The stringers shown in Fig. 1 may be said to comprise attaching webs 1 having opposite longitudinal beads 2 to which the metallic members 3 of the fastener are attached. In

such a stringer the strength and evenness of the beads is of very great importance and my present invention contemplates a strip which may be woven with the desired beads or ribs for fastener engagement which will have a maximum of strength and uniformity and yet be capable of production at reasonable cost and without undue expense for necessary equipment.

In disclosing the principles involved in my present invention I will describe stringers of characteristic weave which fulfill these requirements. It may be said in general before proceeding to the detailed description of the forms shown, that structurally my present strip or stringer comprises a flat web 1 which may be conveniently attached to the article on which the fastener is to be used, and in weaving integral therewith, a pair of beads so woven as to be exposed or exposable as a free edge on the stringer 1. In general I may also state that I produce these beads 2 by a segregation of longitudinal or warp threads. These I displace with reference to each other and with reference 70 to the attaching web and secure them in such segregation and relation by attaching them to the web by weft threads common to the web in whole or in part.

In doing this I may proceed as shown in 80 Figs. 2, 2^a, 2^b, 2^c and 2^d. In these I have indicated the warp threads as at W with the segregated longitudinal threads or members indicated at W¹ and W² and the filling or weft at F. It will be seen from Fig. 2 that 85 the filling F traverses the warp in the tape proper regularly, passes through a series of warp threads W¹ in enclosing relation to a cord or stuffer C, passes through the fabric at right angles, interlaces with another set or 90 warp threads W² on the opposite side also disposed about a cord or stuffer C¹, and returns through the warp of the tape proper. In doing this the shuttle has followed a sequence which I have endeavored to illustrate in Fig. 95 2^b, the shuttle being indicated at S. At (A) I have shown the first laying of the weft thread directly through the warp of the tape proper and out between the two cords C and C¹. At (B) I have shown the shuttle as hav- 100

ing turned about one group of longitudinal members W^1 to a free position from which it moves as at (C) through the second warp group W^2 as at D between the two groups to complete the cycle.

At this point in the weave, the two following picks perform the same operation except that they are woven first about the lower stuffer C^1 and then about the upper stuffer C , as shown in Figs. 2^a and 2^c. Referring to Fig. 2^c, on the throw of the shuttle indicated at (E) the weft thread is laid directly through the warp of the tape proper and out between the two cords C and C^1 . At (F) the shuttle 10 has turned about the lower cord C^1 and through the group of warp threads W^2 to a free position from which it moves as at G 15 around the upper cord C through the warp group W^1 returning as at H between the two 20 groups to complete the cycle.

This weave, by the looping of the filler upon itself, produces a line, indicated in cross section at T in Figs. 2 and 2^a, upon which there are 50% extra filling yarn thicknesses, tending 25 to produce a tape whose beaded edge describes a convex curve. This feature is desirable because in later operations the affixing of the metal fastener members tends to crimp the beaded edge and thus shorten that side of 30 the tape. This is undesirable but is corrected by my invention.

In Figs. 3, 3^a, 3^b and 3^d, I have shown a form to be woven with two shuttles in operation at once on a cross shot loom, thus weaving tape 35 and beads at the same time and at as great a speed as the tape alone would be woven with a single shuttle.

In Fig. 3 the filling from the upper of two shuttles S and S^1 interlaces with warp ends 40 W^1 around the upper bead C , while the filling from the lower shuttle S^1 is weaving in the tape proper. On the second pick both shuttles return through the same warp threads 45 respectively except that the upper shuttle S also passes under one or more ends of the main warp as shown at (O) this binding the inside edge of the bead covering fabric to the tape fabric proper. This is shown diagrammatically in Fig. 3^b wherein the first picks 50 of the two shuttles working in unison pass around the upper warp group W^1 and through the warp of the tape proper, as indicated at (J) in said figure. The second picks return in the same paths, as indicated at (K). On 55 the third and fourth picks, Fig. 3^a, the upper shuttle S passes through the warp of the tape proper while the lower shuttle S^1 weaves about the lower cord C^1 through warp W^2 , passing over one or more ends of the warp 60 W to bind the lower cord covering fabric into the fabric of the tape proper. This is also shown diagrammatically in Fig. 3^b wherein the third picks of the two shuttles pass through the warp of the tape proper and 65 around the lower bead C^1 , as indicated at (L),

returning through the same paths, as indicated at (M).

It will thus be noted that the shuttle S which first looped the upper bead C on the two picks (J) and (K) then passed through the warp of the tape proper on picks (L) and (M) and conversely that shuttle S^1 which first wove through the tape proper on picks (J) and (K) later looped the lower bead C^1 on picks (L) and (M).

In Fig. 4 the modification indicated may be produced on a cross shot loom in which three shuttles in operation at the same time weave upper bead, tape fabric and lower bead at the same speed as a single shuttle in a plain tape. The shuttle S^1 , filling F^1 , warp W^1 always weave together to form the upper bead. Shuttle S, filling F, warp W always weave together in the tape proper while shuttle S^2 , filling F^2 and warp W^2 always 75 form the lower bead around cord C^1 . This is shown diagrammatically in Fig. 4^a wherein the shuttle S weaves back and forth in a straight path to produce the tape proper. Shuttles S^1 and S^2 weave fabrics above and 80 below the cords C and C^1 and also interlace at each end of their travel with one or more threads of the warp W, this tying the edges 85 of the tape covering fabrics into the fabric of the tape proper.

In this construction, therefore, the tape itself may be of one color and sizes or variety of yarns, while the bead coverings may be of different colors and sizes or kinds of yarn.

Figs. 2^d, 3^d, 4^d indicate the positions of weft in the fabrics shown in Figs. 2 and 2^a, 3 and 3^a and Fig. 4, respectively. Parallel curved or straight lines indicate that a shuttle returns on the same path through same warp.

I have indicated in Figs. 2^a, 2^b, 2^c and 2^d, Figs. 3, 3^a, 3^b and 3^d, Figs. 4, 4^a and 4^d, structures and weaves in which the beads are formed in the fabric by being fabricated therein with weft. Figs. 3 and 3^a illustrate specific developments whereby it is possible to produce a beaded tape at the same speed as a plain tape except for lessened loom speed due to somewhat increased complication of mechanism. These same constructions may be produced at still less speed by using several 110 shuttles in series instead of in unison and there are other ways of attaching cords to tape by shuttle thread inclusion which will occur to those skilled in the art of weaving but which are not shown.

In Figs. 5 and 5^a, I have tried to illustrate a method of forming longitudinal beads to a tape by means of warp inclusion. In this and similar possible constructions the filling F traverses the warp for the full width of 125 the tape and beads and were it not for the doup threads D and D^1 and the stuffers C and C^1 would produce an ordinary flat tape. The ends D and D^1 of a special warp function to produce what is known as Roman cords on 130

each side of the fabric by means of the leno or gauze weave. As shown here, at each pick of the weave the thread D is brought from under the previous thread of weft across the top of stuffer C and under the weft, being returned over the stuffer C and under the weft on the pick following. At the same time the doup thread D¹ is crossed under stuffer C¹ from a position over the previous weft thread 10 to a position over the pick under discussion and returned to its starting position on the pick following. Thus by this or similar constructions pairs of cords may be bound into positions opposite each other on opposite 15 sides of a tape as it is being woven.

The tape or web portion of the stringer may be of any desired weave or pattern, that shown in the drawings being merely employed for simplicity of illustration.

20 The cords or stuffers C and C¹ may be single strands spun to the desired size in cotton, or other material; they may be formed of smaller yarns twisted or braided together to form a cord of the desired size; or they may be a 25 number of separate threads which will be bound into bead forms by the weaving process. These beads, if woven as in Fig. 4 or 5, may be of contrasting color to that of the tape proper. This assists in inspecting 30 finished fasteners as the position of the metallic fastener members can be better checked where the beads are clearly visible and distinct from the tape proper. These constructions in Figs. 4 and 5 also make possible the 35 use of yarns, different in size or material from those in the tape proper, in the weaving of the beads.

What I therefore claim and desire to secure by Letters Patent is:

40 1. An integral woven stringer for a fastener series comprising an attaching strip and interwoven tubular portions on opposite sides of the strip along one edge thereof having one or more systems of filling additional to and 45 separate from that used in the attaching portion.

2. A woven stringer for separable fasteners comprising a web including a group of weft threads woven in a single operation with 50 warp threads to provide a pair of longitudinal tubular portions disposed at opposite sides of said web, and stuffers of a diameter relatively large with respect to said threads enclosed in the tubular portions of the stringer.

55 3. A woven stringer for separable fasteners comprising a web including two groups of weft threads coincidentally or alternately woven in a single operation with warp threads to provide a pair of longitudinal tubular portions disposed at opposite sides of said web, and stuffers of a diameter relatively large with respect to said threads enclosed in the tubular portions of the stringer.

4. A woven stringer for separable fasteners comprising a web including three groups

of weft threads simultaneously or consecutively woven in a single operation with warp threads to form said web and provide a pair of longitudinal tubular portions disposed at opposite sides of said web, and stuffers of a diameter relatively large with respect to said threads enclosed in tubular portions of the said stringer. 70

5. An integral woven stringer for a fastener series comprising an attaching strip having interwoven tubular portions on opposite sides thereof along one edge, each tubular portion having one or more systems of warp additional to that used in the attaching portion, and a stuffer in each tubular portion. 75

6. An integral woven stringer for a fastener series comprising an attaching strip having tubular interwoven portions on opposite sides thereof and along one edge, and a stuffer in each tubular portion. 80

In testimony whereof I affix my signature.
WILLARD CHARLES FRENCH.
